United States Patent Office

Des. 198,546
Patented June 30, 1964

198,546

FRUIT TRAY

Theodore S. Loeser, Nixon, N.J., assignor to Union
Carbide Corporation, a corporation of New York

Filed June 19, 1963, Ser. No. 75,434

Term of patent 14 years

(Cl. D58—13)

Fig. 1.

Fig. 2.

FIG. 1 is a perspective view of the fruit tray showing my new design.

FIG. 2 is a bottom plan view of the fruit tray shown in FIG. 1.

I claim:

The ornamental design for a fruit tray, substantially as shown.
